UNITED STATES PATENT OFFICE

ALFRED J. MUHLBACH, OF SOUTH PASADENA, CALIFORNIA, ASSIGNOR TO THE BOYLE MANUFACTURING COMPANY, INC., OF LOS ANGELES, CALIFORNIA, A CORPORATION OF CALIFORNIA

PROCESS OF MAKING METALLIC CASKS

Application filed May 15, 1926. Serial No. 109,230.

This invention relates to metallic casks and process of making the same.

An object of the invention is to produce a unitary integral metallic cask or bilged barrel body by an improved process, consisting in first cutting out a blank of sheet metal and forming the same to provide a substantially cylindrical tube, then forming the cylindrical tube into bilge shape by a series of expanding operations separately applied to different zones of the cylindrical tube to thereby effect a step by step gradual drawing of the metal into bilge form without imposing excessive strains upon the metal or unequally drawing the same at different points along the barrel body.

Another object of the invention is to provide an improved cask or barrel of bilge form made up from a unitary blank, which has integral corrugations encircling the same at spaced points along the bilge surfaces.

Other and further objects of the invention will more clearly appear from the description and claims hereinafter following.

In the drawings, Fig. 1 represents a longitudinal, sectional view of the cask at the finish of the first expanding operation, showing in dotted lines the cylindrical blank prior to the expanding operation, and illustrating in elevation the die sections for effecting the expansion of the tube. Fig. 2 is an end elevational view of the die sections illustrated in Fig. 1. Fig. 3 is an elevational view of the cask as it appears after the finish of the first expanding operation. Fig. 4 is a view similar to Fig. 1, showing the tube at the end of the second operation thereon by means of the die sections. Fig. 5 is an elevational view of the cask body as it appears after being subjected to the second expanding operation. Fig. 6 is a view similar to Figs. 1 and 2 showing the final expanding operation of the tube. And Fig. 7 is an elevational view of the completed barrel body as it appears following the third or final operation.

The herein described process consists in first cutting out a rectangular blank of metal of suitable gauge having the maximum strength and adapted to be drawn under relatively heavy pressure, and then bending the

blank longitudinally into cylindrical form and welding the transverse meeting edges of the blank to provide a unitary integral cylindrical tube of the type shown in dotted lines in Fig. 1.

The tube thus formed is then uniformly and simultaneously swaged or expanded in the opposite end annular zones 10 and 11, with a minimum of expanding or swaging action upon the material adjacent the extremities of the end portions, and with progressively greater expanding or swaging action upon the metal inwardly from said extremities a pre-determined distance, approximating one-fifth of the length of the tubular body at each end thereof, and at the inner extremities of the swaged portions 10 and 11, each of the same is further swaged outwardly simultaneously with the swaging of the end portions to form the outwardly extending annular corrugations 13 and 14, as shown in Figs. 1 and 3.

The dies for accomplishing the above simultaneous swaging of the end zones of the cylindrical tube preferably consist of a plurality of elongated die sections 15, segmental in cross section, and radially disposed about the longitudinal central axis of the tube, and of a length corresponding approximately to the length of the cylindrical tube before the swaging action is begun by the dies. The inner faces of said die sections are provided with longitudinally spaced recesses providing spaced wedge surfaces 16 and 17 adapted to co-act with the longitudinally arranged inter-connecting wedges 18 and 19, whereby longitudinal movement of the wedges 18 and 19 to traverse the wedge surfaces of the conical wedge surfaces of the die sections, effects radial movement of the die sections and consequent drawing or expanding of the material at opposite end zones of the tube. The outer face of each die section is provided with longitudinally spaced oppositely tapered enlargements 20 and 21, each of said enlargements terminating at its inner extremity in a rib 22, the ribs of all of the die sections 15-15 coinciding and forming a rib extending annularly about the die sections. Any suitable means, not shown, may be utilized, if

necessary, for maintaining the die sections in longitudinal alinement.

With this arrangement of die sections, the cylindrical tube is fitted over the dies and the wedges actuated to expand the cylindrical tube in the manner above described in detail.

The partially swaged body shown in Fig. 3 is then subjected to the second operation.

10 Said operation consists in swaging two spaced intermediate zones 23 and 24 by means of suitable dies, the swaging action being carried somewhat farther than occurs in the first operation so as to produce zones 23 and 24 which taper in opposite directions, and which are progressively of greater diameter toward the central zone of the cask or barrel. During the second swaging operation, annular corrugations 25 and 26 are formed adjacent 15 to the inner extremities of the intermediate zones 23 and 24 as most clearly shown in Figs. 4 and 5.

The dies used to accomplish the second operation are practically identically similar to those utilized in connection with the first operation, except that the die sections are of sufficiently less length than the die sections 15—15 so as to space the enlarged portions 27 and 28 a less distance apart in order to cause the same to operate upon the intermediate zones of the barrel body. Wedging means similar to the wedging means 18 and 19 may be used as shown in Fig. 4.

The third step or operation consists in 35 swaging or expanding the central zone 29 which is of the character shown in Figs. 4 and 5 and is disposed between the intermediate zones 23 and 24. The central zone 29 is swaged or expanded outwardly to bilged form of somewhat greater diameter than the end and intermediate zones of the barrel, as shown in Figs. 6 and 7. The third operation is accomplished by providing suitable die sections 40 having outer longitudinally disposed arcuate faces which operate upon the central portion 29, and which die sections are radially expanded by longitudinal movement of the wedge 31 to effect the desired purpose. Suitable heads, not shown, may be utilized for 45 closing the open ends of the barrel body as desired.

The completed barrel body produced as a result of the swaging operations above described comprises a metallic body including a 50 plurality of separately formed zones which collectively are arranged in bilged or oblate formation, with integral pressed or formed corrugations 33 and 34 separating the zones 32—32, said corrugations being pressed in 55 the material of which the cask body is made and being of substantially uniform depth and of a diameter corresponding to the diameter of the zones with which they are associated.

It will be appreciated that by utilization of 60 the above described process the cylindrical

tube is separately swaged or expanded at a plurality of zones successively, resulting in independent drawing of the metal at pre-determined localized portions while the remainder of the tube is free of pressure, thereby 70 obviating tearing of the metal and weaknesses which would result from the expanding of the cylindrical tube to the desired bilged form in a single operation.

While I have herein shown and described 75 what I now consider the preferred manner of carrying out the invention, the same is merely illustrative, and I contemplate all changes and modifications that come within the scope of the claims appended thereto.

I claim:

1. A process of making a bilged cask or barrel body from a substantially cylindrical metallic tube consisting in simultaneously and uniformly applying expanding pressure 85 to spaced local annular zones while the remaining portions of said cask or barrel are free from pressure and independently expanding the tube between said spaced zones to a greater diameter than said spaced zones 90 while the latter are free from pressure.

2. A process of making a bilged cask body from a substantially cylindrical metallic tube consisting in simultaneously and uniformly applying expanding pressure to spaced annular zones, while the remaining zones are free from pressure; and independently expanding the tube at spaced annular zones 95 between said first zones to a greater diameter than the latter.

3. A process of making a bilged cask body from a substantially cylindrical metallic tube consisting in simultaneously and uniformly applying expanding pressure to spaced annular zones, while the remaining zones are 100 free from pressure; independently expanding the tube at spaced annular zones between said first zones to a greater diameter than the latter, and expanding the tube between the second mentioned zones to a greater diameter 105 than the first and second mentioned zones.

4. The process of making a bilged cask or barrel body from a substantially cylindrical metallic tube, which consists in applying expanding pressure to the annular end zones to 110 produce separated end zones of inwardly increasing expansion, and in independently applying expanding pressure to the intermediate zone to enlarge the diameter thereof.

5. The process of making a bilged cask or barrel body from a substantially cylindrical metallic tube, which consists in applying expanding pressure to the annular end zones to 115 produce separated end zones of inwardly increasing expansion, and in then independently applying expanding pressure to the intermediate zone to enlarge the diameter thereof, to an extent at least equal to the diameters of the contiguous portions of previously expanded end zones.

6. The process of making a bilged cask or
barrel body from a substantially cylindrical
metallic tube, which consists in simultaneous-
ly applying expanding pressure to both end
5 zones to produce separated end zones of in-
wardly increasing expansion, and in then ap-
plying expanding pressure to the intermedi-
ate zone to enlarge the diameter thereof.

7. The process of making a bilged cask or
10 barrel body from a substantially cylindrical
metallic tube, which consists in simultaneous-
ly applying expanding pressure to both end
zones to produce separated end zones of in-
wardly increasing expansion, and in then ap-
15 plying expanding pressure to the intermedi-
ate zone to enlarge the diameter thereof, to
an extent in its medial portion greater than
the diameter of the contiguous portions of
the previously expanded end zones.

20 In witness that I claim the foregoing I have
hereunto subscribed my name this 21st day
of April 1926.

ALFRED J. MUHLBACH.
